US00D875715S

(12) **United States Design Patent** (10) **Patent No.:** **US D875,715 S**
Cheney (45) **Date of Patent:** **** Feb. 18, 2020**

(54) **WIRELESS SPEAKER**

- (71) Applicant: **Zagg Amplified, Inc.**, Midvale, UT (US)
(72) Inventor: **John Craig Cheney**, Orem, UT (US)
(73) Assignee: **ZAGG Amplified, Inc.**, Salt Lake City, UT (US)

(**) Term: **15 Years**

(21) Appl. No.: **29/613,881**

(22) Filed: **Aug. 14, 2017**

Related U.S. Application Data

- (63) Continuation of application No. 29/550,464, filed on Jan. 4, 2016, now Pat. No. Des. 794,604.

(57) **CLAIM**

The ornamental design for a wireless speaker, as shown and described.

DESCRIPTION

FIG. 1 is a front perspective view of a wireless speaker.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings illustrate portions of the wireless speaker which form no part of the claimed design.

1 Claim, 6 Drawing Sheets
